UNITED STATES PATENT OFFICE.

WILLIAM C. FISHER, OF MIDDLETOWN, CONNECTICUT, ASSIGNOR TO THE RUSSELL MFG. CO., OF MIDDLETOWN, CONNECTICUT, A CORPORATION.

MACHINE-GUN CARTRIDGE-CONVEYER.

1,197,280.

Specification of Letters Patent. Patented Sept. 5, 1916.

Application filed March 13, 1916. Serial No. 83,761.

To all whom it may concern:

Be it known that I, WILLIAM C. FISHER, a citizen of the United States, residing at Middletown, in the county of Middlesex and State of Connecticut, have invented a new and useful Improvement in Machine-Gun Cartridge-Conveyers; and I do hereby declare the following, when taken in connection with the accompanying drawings 10 and the characters of reference marked thereon, to be a full, clear, and exact description of the same, and which said drawings constitute part of this application and represent, in—

15 Figure 1 a broken view in side elevation of a machine-gun cartridge-conveyer constructed in accordance with my invention, showing three cartridges therein. Fig. 2 a view of the belt in vertical transverse section on the line *a—b* of Fig. 1. Fig. 3 a schematic transverse section of one of the 20 two strips of woven fabric used in the production of the conveyer.

My invention relates to an improvement 25 in the belt-like cartridge-conveyers designed for use in conveying cartridges through the firing-chamber of a rapid-fire machine-gun, the object being to reduce the cost of producing such conveyers to the minimum, as 30 well as to produce an efficient, convenient and durable article.

With these ends in view, my invention consists in a machine-gun cartridge-conveyer having certain details of construction 35 as will be hereinafter described and pointed out in the claims.

In carrying out my invention as herein shown, I employ two corresponding strips of woven fabric 2, 3, placed face to face and fastened together by metal clamps 4 secured in place by eyelets 5, the said clamps 4 being regularly spaced apart at the distance required for producing pockets 6 for the reception of cartridges 7. To 45 adapt the conveyer to grip the shouldered, bullet ends of the cartridges, the lower edges of the strips 2, 3, are thickened as at 2^a and 3^a, so as to contract or reduce in diameter the lower ends of the cartridge-receiving pockets 6. For this purpose, the loom used in producing the woven strips 2 and 3, is set to weave a strictly single ply fabric of warp threads 8 and weft threads 9, and also set to change the weave at the 55 point where it is desired to begin to thicken

the lower portion of the strips so that although the weave is continued as a single ply weave, extra warp threads are introduced and interwoven so as to materially thicken the lower portions of the strips, the 60 extra warp threads so introduced being illustrated in Fig. 3 by the threads 10. In other words, the loom is set so as to produce a single ply fabric, in which the weave is changed, as for instance, to a twill weave 65 which permits the introduction of an excess of warp threads throughout that portion of the fabric which it is designed to thicken. The fabric thus produced is a combination of plain weaving and twill 70 weaving, but retains its characteristic as a single-ply fabric. The loom is also set to produce the familiar tubular or corded edge well known in the art and illustrated in Fig. 3 by the loop 11 filled with cords 12. 75

If preferred, the loom may be set so that at the point where the weave is changed from plain weaving to weaving of another type of weaving, larger warp threads may be introduced and interwoven in addition 80 to the standard warp threads used in the plain woven portions of the fabric. But, however, the thickening of the lower portions of the strips is effected for the purpose stated, the weaving of the entire width 85 of the strip will be characterized as a single-ply weaving. In any event the additional threads will be themselves actually interwoven into the fabric.

By weaving the strips on the single-ply 90 plan, I am enabled to operate the loom and produce the woven strips in half the time in which they can be produced if they are woven on the double or two-ply plan, this rule holding true if the number of plies is 95 increased. Thus a single-ply strip can be produced in one third of the time that would be required for a three-ply strip and so on. I am therefore enabled by my invention to effect a great economy of time 100 and labor in the manufacture of the thickened strips, as well as a substantial economy of thread.

I claim:—

1. A woven machine-gun cartridge-conveyer consisting of two woven strips placed face to face and secured together at regular intervals to form cartridge-receiving pockets, the said strips being woven as single-ply strips having their lower portions 110

changed in weave for the introduction of interwoven additional threads to thicken them, whereby the lower portions of the cartridge-receiving pockets are reduced in diameter and the pockets thus conformed to the shoulder-portions of the cartridges.

2. A woven machine-gun cartridge-conveyer composed of two woven strips placed face to face and attached together at regular intervals to form cartridge-receiving

pockets, the said strips being woven as single-ply strips having their lower portions changed from plain weaving to twill weaving to permit the introduction of interwoven additional warp threads to thicken them, whereby the lower portions of the cartridge-receiving pockets are reduced in diameter and the pockets thus conformed to the shoulder-portions of the cartridges. 15

WILLIAM C. FISHER.
